UNITED STATES PATENT OFFICE.

MARIO PERUZZI, OF WILKES-BARRE, PENNSYLVANIA, ASSIGNOR TO PLANTERS NUT AND CHOCOLATE COMPANY, OF WILKES-BARRE, PENNSYLVANIA.

DESIGN FOR A DISPLAY CARTON.

Application filed May 26, 1925. Serial No. 13,570. Term of patent 3½ years.

To all whom it may concern:

Be it known that I, MARIO PERUZZI, citizen of the United States, residing at Wilkes-Barre, in the county of Luzerne and State of Pennsylvania, have invented a new, original, and ornamental Design for Display Carton, as shown in the accompanying drawing and described in the following specification.

I claim:

The ornamental design for a display carton as shown.

MARIO PERUZZI,
